United States Patent Office.

MARK SAFFORD, OF BOSTON, MASSACHUSETTS.

Letters Patent No. 64,578, dated May 7, 1867.

IMPROVEMENT IN LAMP-EXTINGUISHERS.

The Schedule referred to in these Letters Patent and making part of the same.

TO ALL WHOM IT MAY CONCERN:

Be it known that I, MARK SAFFORD, of Boston, in the county of Suffolk, and State of Massachusetts, have invented a new and useful Improvement in Lamp-Burners; and I do hereby declare the following to be a full, clear, and exact description of the same, reference being had to the accompanying drawings, in which—

Figures 1 and 2 are side elevations; and

Figure 3 a section of a lamp-burner containing my invention.

Figure 4 is a rear side elevation of the wick-tube with my invention attached thereto.

The invention in question is an improvement in that class of lamp-burners in which a cap or plate is employed for covering the top of the wick-tube and extinguishing the flame, as well as for the purpose of preventing waste of the contents of the lamp by evaporation, and the odor of them from escaping into the apartment.

The invention consists in applying the extinguisher to the burner in such a manner that it shall be actuated by a cam applied to the wick-elevator shaft, so that the rotation of this shaft, in the act of elevating the wick, when lighting the lamp, shall first move the extinguisher from off the wick-tube, and then raise the wick above the tube the requisite distance, the extinguisher subsequently coming back to place upon the lowering of the wick within its tube.

In the above-mentioned drawings, *a* denotes the body of the burner, and *b* its wick-tube, *c* being its notched wick-elevating wheel, and *d* the wire or shaft carrying the wheel, the parts thus described constituting the ordinary burner. The extinguisher is shown as composed of a flat plate, *e*, having at top a lateral bend or lip, *f*, to shut over upon the top of the wick-tube when the flame is extinguished, the plate *e* being supported at bottom by a horizontal wire or rocker-shaft, *g*, extending across, and supported by, the burner, and situated in a plane with, and parallel to, the shaft *d*. A tripper or finger, *h*, is affixed to the outer end of the shaft *g*, and lies against the periphery of a cam, *i*, secured to the wick-elevating shaft *d* between its milled head and the burner, the arrangement of the finger *h* and cam *i* being such that, on revolving the shaft *d*, the cam will so actuate the finger as to cause a partial revolution of the shaft *g*, and remove the extinguisher from off the wick-tube before the wick reaches the top of the same, the extinguisher being forced up to or towards the wick-tube by the action of a spring, *j*, suitably applied within the burner, and bearing against it. By turning the shaft *d* in one direction, that is, to the right, the extinguisher will be removed from off the wick-tube, and the wick subsequently raised above the tube into a position to enable it to be inflamed, it being understood that the length of the wick is to be first so adjusted that, when the tube is covered, the wick shall be some distance below its top, in order to give time for the extinguisher to be moved out of its path before it reaches that point. By reversing the movement of the shaft *d* the wick will first be lowered into its tube, and the extinguisher afterwards forced over upon the tube, thus extinguishing the flame, and preventing escape of odor, or waste of the contents of the lamp, as well as doing away with the dangerous habit of blowing out the flame. The shape of the cam *i* is shown in fig. 1 of the drawings as composed of the segment of a circle, *a'*, and a flat surface, *b'*, the length of the portion *a'* determining the length of time requisite to detain the extinguisher from off the wick-tube, as the extinguisher will be free to cover the tube when the flat surface *b'* of the cam and the finger *h* are in contact.

I claim so applying the extinguisher to the burner that its movements shall be actuated by the wick-elevating shaft, and by the same act which raises and lowers the wick, substantially in manner and for the purpose as described.

I also claim the device for causing the above-described movement of the extinguisher, consisting of the finger *h* and cam *i*, applied to the shafts *g* and *d*, the extinguisher being moved in one direction by the spring *j*, the whole being arranged and operating together in manner as above set forth and explained.

MARK SAFFORD.
